DESIGN FOR A HANDBAG OR SIMILAR ARTICLE

Ernest Konelsky, Paris, France

Application October 12, 1936, Serial No. 65,257

Term of patent 7 years

To all whom it may concern:

Be it known that I, Ernest Konelsky, a citizen of the Union of Soviet Socialist Republics and resident of Paris, France, have invented a new, original, and ornamental Design for Handbags or Similar Article, of which the following is a specification, reference being had to accompanying drawing forming part thereof, in which,

I claim:

The ornamental design for a handbag or similar article substantially as shown and described.

ERNEST KONELSKY,
